CLAIM

The ornamental design for a camera device with adjustable base, as shown and described.

DESCRIPTION

FIG. 1 is a front and right side perspective view of a camera device with adjustable base showing our new design;
FIG. 2 is a front view thereof;
FIG. 3 is a back view thereof;
FIG. 4 is a right side view thereof;
FIG. 5 is a left side view thereof;
FIG. 6 is a top view thereof; and,
FIG. 7 is a bottom view thereof.

The broken lines depict portions of the camera device with adjustable base in which the design is embodied that form no part of the claimed design.

The zig-zag broken lines shown at the cable end portion of the camera device with adjustable base in FIGS. 1 and 4–7 represent boundary lines that define the bounds of the claim and form no part of the claimed design.
